PROCESS FOR THE OXIDATION OF WHITE MINERAL OILS TO DICARBOXYLIC NAPHTHENIC ACIDS

Joseph Winkler, Queens, N. Y., assignor to American Collo Corporation, New York, N. Y.

No Drawing. Application March 30, 1954,
Serial No. 419,900

3 Claims. (Cl. 260—514)

White mineral oils are considered intermolecular mixtures of naphthalene rings with paraffin side chains. They are practically free of aromatic and naphthalene paraffin side chain compounds and solid paraffin waxes. White mineral oils are compounds which have the following basic structure:

I

Depending on its molecular weight, n is in the range of 5 to 40. In order to make a white mineral oil, the mineral oil distillate, produced from crude oil, must be properly purified. This purification is done normally by exhaustive treatment with sulphuric acid monohydrate and later with large amounts, in two to 10 washes, with oleum, containing 20% and more of free SO₃. In order to remove from the sour oil the sulphonated products, this oil is again treated in the last wash with sulphuric acid monohydrate. In the final treatment, the sour white mineral oil is deacidified with alcoholic solutions of caustic soda and absorbent clay in order to obtain an entirely acid-free, water-free white mineral oil.

It is known that white mineral oils can be oxidized with air, with or without catalysts, under atmospheric pressure or at pressures up to 50 atmospheres; at temperatures ranging from 100° to 200° C., to monocarboxylic acid products. These products, however, are dark colored and malodorous and their sodium salts cannot be separated by salting out. Lighter monocarboxylic acid products are obtained by partial oxidation of white mineral oils, when only a part of the oil is converted by oxidation to corresponding monocarboxylic acids having the following basic structure:

II

The unchanged, non oxidized main part of the white oil, after separation from the produced acids (II), by conventional methods of selective extraction, is returned back to the oxidation process. The produced monocarboxylic acids are utilized for the production of industrial soaps, soap based greases, etc. However, because of the low quality of these acids (dark color, sharp odor), the air oxidation of white mineral oils to monocarboxylic acids was used industrially only during World War II, in Germany, and later abandoned when fatty acids again became abundant.

The object of this invention, is to provide a process for the manufacturing of dicarboxylic naphthalene acids from white mineral oils by a new two-step liquid phase oxidation, which comprises:

2

Step No. 1.—Exhaustive air oxidation

Exhaustive oxidation of white mineral oils with air under pressure at temperatures of from 100° to 200° C., in the presence of a catalyst. As an intermediate product there is obtained a mixture of a small amount of unchanged white mineral oil (I) with more than 80% of the following monocarboxylic acids: (II) naphthalene acids; (III) hydroxy-naphthalene acids; (IV) carbonyl-naphthalene acids; and their inner- and hetero-esters (V, VI, and VII).

Step No. 2.—Exhaustive oxidation with an aqueous solution of a peroxide salt

The product from the exhaustive air oxidation as described above, is a two-phase, malodorous, dark brown, highly viscous oil. This intermediate material, is according to the present invention further exhaustively oxidized with an aqueous concentrated solution of a peroxide salt, at temperatures not higher than 100° C. I have found that any peroxide salt which is soluble in water performs in the same manner and gives the same desired result; i. e. the formation of dicarboxylic naphthalene acids. Such cheap commercial peroxide salts soluble in water and suitable for my process are for example, hydrogen peroxide, ammonium-, sodium and potassium persulphates, alkaline earth persulphates; ammonium, sodium, potassium and alkaline earth permanganates; ammonium, sodium, potassium and earth-alkali chlorates and perchlorates; peracetic-, propionic- and perbutyric acids, nitric acid etc. This new oxidation step serves the important purpose of transforming the valueless products from the first oxidation step into valuable, predominantly dicarboxylic naphthalene acids.

It is believed that these dicarboxylic naphthalene acids have the following basic structure:

VIII

Depending on its molecular weight, m is in the range of 0 to 25. This mixture of homologous dicarboxylic naphthalene acids contains, besides small amounts of unchanged white oil (I), one to 5% of volatile, low molecu-

lar fatty acids, produced during the first step of the oxidation process, due to the splitting of the long aliphatic chain by the oxygen of the air; $-(C_2)_nCH_3$, attached to the cyclopentane ring in position 3, into two separate monocarboxylic acids. Nevertheless, this finely oxidized material has a much gentler odor of fatty acids, its viscosity is much lower, its color is straw-yellow, and its specific gravity is much higher. An additional steam distillation removes the low molecular fatty acids leaving an almost odorless product, which contains more than 80% of dicarboxylic naphthenic acids. In order to free them from the non-saponifiable matter, an extraction with an alcohol-water mixture removes the acids, leaving insoluble the unsaponifiable matter. A subsequent distillation of the water-alcohol solution of the dicarboxylic naphthenic acids removes the solvent mixture, and the mixture of the dicarboxylic naphthenic acids can be finally fractionated under vacuum into narrow cuts of the individual homologs of the dicarboxylic naphthenic acids, which are believed to have formula as shown in (VIII) above. These acids are very valuable starting materials for purposes of further syntheses, in which aliphatic and aromatic dicarboxylic acids were previously being used, such as for example, maleic, sebacic, succinic and adipic acids in the aliphatic series, and phthalic, and terephthalic acids in the aromatic series. Consequently, for the first time through my new two-step oxidation process a new class of dicarboxylic naphthenic acids is created, which lends itself to the manufacture of industrially valuable esters, salts, polyesters, polyamides, polyurethanes etc., from which different synthetic fibers, plastics, and elastomers can be cheaply produced.

The following examples are illustrative of this invention:

EXAMPLE 1

As the starting commercial oil, a semi-refined white oil, called "AHC Process Oil," made by Socony Vacuum Co., was selected. Its physico-chemical properties were as follows:

Hot-acid test—black; n_D^{20} —1.4808; d_4^{20} —0.886; dist. range °C./10 mm. of 5 to 95%—173 to 223; flash point—158° C.; viscosity in centistokes/20° C.—31; aniline point—plus 81° C. This oil was exhaustively refined with a 20% oleum to a white oil, which had the following physico-chemical properties:

Hot-acid test—water-white; n_D^{20} —1.407; d_4^{20} —0.869; dist. range °C./10 mm. of 5 to 95%—176 to 246; flash point—148° C.; viscosity in centistokes/20° C.—24.4; aniline point—plus 91° C.; molecular weight—292; pour point—less than minus 50° C.; percent aliphatic side chains—49; percent naphthenic rings—51.

100 pounds of above white mineral oil were exhaustively oxidized at a temperature below 160° C., in the presence of a catalyst belonging to the class of fatty acid salts of polyvalent heavy metals. This oxidation was conducted in a stainless steel autoclave, equipped with a turbomixer, and having a total capacity of 60 gallons. The pressure during the air oxidation was kept below 10 atmospheres. Every hour a sample of the oxidized oil was withdrawn from the autoclave and analysed for the carbonyl number by the method of Bertram, described in the Journal Inst. of Petr. Techn., 34, 930 (1948). The air oxidation was considered as finished as soon as in an hour interval the carbonyl number did not increase by more than one unit. Further oxidation would be useless, because instead of increasing the content of the carbonyl-naphthenic acids, a considerable resinification would take place. The oxidation was considered as finished after a total oxidation time of 15 hours. From 100 pounds of the starting white oil, 101 pounds of the oxidized product were obtained. Analysis of this product:

Color—dark brown; appearance—two separate layers; odor—sharp stingy of burned oil; d_4^{20} —0.995; n_D^{20} —1.4789; visc. in centistokes/20° C.—896; dist. range/10

mm.—5%/131° C., 75%/256° C.; carbonyl No. 98; unsaponif. matter—20%; naphthenic and hydroxynaphthenic acids—51%; carbonyl-naphthenic acids—37%; volatile fatty acids—2%.

5 This two-phase mixture without separating is subsequently oxidized in the same autoclave with a 35% aqueous solution of potassium permanganate as follows:

The 101 pounds of the product are saponified and further oxidized with about 120 pounds of a 35% aqueous solution of potassium permanganate. This amount was calculated from the quantitative analysis by using an excess of one mole of the $KMnO_4$ for the carbonyl group in each mole of the carbonyl-naphthenic acids; in excess of two moles of $KMnO_4$ for the methoxy-group in each mole of the hydroxy-naphthenic acids, and in excess of three moles of $KMnO_4$ for the methyl group in each mole of the naphthenic acids.

First the 101 pounds of the air oxidized oil were heated to a temperature of about 70° C. At this temperature, while thoroughly stirring, at atmospheric pressure, the calculated amount of the above mentioned $KMnO_4$ aqueous solution was slowly added and during the addition, the temperature was maintained at about 70° C. by the use of a cooling bath. After the exothermic reaction was completed the mixture was allowed to cool to room temperature, at which temperature it was maintained while continuously stirring for about 24 hours. Every hour a sample of the oxidized product was withdrawn and its saponification number was determined. The reaction was considered as finished when in an hour interval no significant increase in the saponification number occurred. Afterwards, the mixture was separated into two layers. The lower, aqueous layer was used for the regeneration of the $KMnO_4$, and the upper, light colored oily layer, was washed thoroughly with hot water, and by steam distillation freed from the volatile low molecular fatty acids. The remaining oil was dried at 100° C., under vacuum and finally filtered. The obtained amount of the final product, which is believed to be predominantly a mixture of homologs of dicarboxylic naphthenic acids (VIII), was analysed and had the following physico-chemical properties:

Color—straw yellow; odor—acidic; viscosity in centistokes/20° C.—165; unsaponifiable matter—23%; saponifiable matter—77%; acid No. 386; saponif No. 391. The product gives typical reaction of dicarboxylic acids.

This mixture of homologs of dicarboxylic naphthenic acids can be easily esterified with polyalcohols, as for example with glycerine, yielding resinous polyesters. However, in some cases, where a more pure polyester is desired, the unsaponifiable matter must be removed. The most economic way to do it is by the extraction of the dicarboxylic naphthenic acids with an aqueous solution of ethyl alcohol, in which the unsaponifiable matter is insoluble. The unsaponifiable matter, which consists mainly of unreacted white oil and some naphthenic alcohols, is returned into the air oxidation process.

EXAMPLE 2

60 As the starting commercial white mineral oil, a product called "Carnation White Oil," and made by L. Sonnenborn and Sons Inc., was selected. Its physico-chemical properties were as follows:

Hot-acid test—water white; n_D^{20} —1.4587; d_4^{20} —0.839; dist. range °C./10 mm. of 5% to 95% was 210 to 225; flash point—185° C.; viscosity in centistokes/20° C.—25; molecular weight—325; pour point—plus 28° C.; aniline point—plus 105° C.; percent aliphatic side chains—28; percent naphthenic rings—72.

65 100 pounds of this white mineral oil were oxidized with air under the same conditions as described in Example 1. After 14 hours of oxidizing, a product was obtained with the following physico-chemical properties:

Color—dark brown; appearance—two-separate layers; odor—sharp stingy like burned oil; d_4^{20} —1.09; n_D^{20} —

1.497; viscosity in centistokes/20° C.—1200; distil. range/20 mm.—5%/62° C.; 50%/225° C.; 75%/280° C.; aniline point—plus 60° C.; acid No. 172; saponif. No. 265; carbonyl No. 128; naphthenic and hydroxynaphthenic acids—31%; carbonyl-naphthenic acids—51%; volatile fatty acids—5%; unsaponif. matter—13%; recovery—107%.

This dark colored, malodorous viscous liquid was oxidized in the same autoclave with a strong 50% aqueous solution of hydrogen peroxide as follows:

For 107 pounds of the air oxidized product about 100 pounds of the 50% hydrogen peroxide solution was used. This amount was calculated in the same way as indicated in Example 1. First the 107 pounds of the air oxidized white oil was heated to a temperature of about plus 50° C. at this temperature, while stirring, at atmospheric pressure, the calculated amount of 100 pounds of the 50% hydrogen peroxide solution was slowly added, and throughout the addition, the temperature was maintained at about plus 50° C. by the use of a cooling bath. After the exothermic reaction was completed, the mixture was allowed to cool off to room temperature, at which temperature it was maintained, while stirring thoroughly for about 20 hours. The oxidation reaction was considered as completed when after one more hour the saponification number of the oxidized product remained almost unchanged. Afterwards, the mixture was separated into two layers. The aqueous layer was discharged and the resulting light colored oily layer was washed with small amounts of warm water and the light volatile low molecular fatty acids removed by a steam distillation. The remaining oil was dried at 100° C. under vacuum and finally filtered.

Analysis of this product: Recovery—115 pounds, 100 lbs. white oil.

Color—straw yellow; odor—acidic; viscosity in centistokes/20° C.—180; unsaponifiable matter—15%; saponifiable matter—85%; carbonyl No. 0; acid No. 370; saponif. No. 372. Gives typical reactions of dicarboxylic acids.

In order to remove the unsaponifiable matter, the oil is reacted with an aqueous solution of caustic soda, and the unsaponifiable matter is extracted from the resulting sodium salts of the dicarboxylic acids with benzene. By acidification with an inorganic acid the pure dicarboxylic naphthenic acids are obtained. By a subsequent vacuum distillation pure individual acids result.

EXAMPLE 3

As the starting commercial white mineral oil, a product called "Superla No. 10a" made by Standard Oil Co. of Indiana was selected. Its physico-chemical properties were as follows:

Hot acid test—water white; n_D^{20} —1.4641; d_4^{20} —0.851; distil. range °C./10 mm. of 5% to 95%—216 to 299; flash point—184° C.; viscosity in centistokes/20° C.—41; molecular weight—345; pour point—plus 25° C.; aniline point—plus 106° C.; percent aliphatic side chains—44; percent naphthenic rings—56.

100 pounds of this white mineral oil was oxidized with air under the same conditions as described in Example 1. After 13 hours of oxidizing, a product was obtained with the following physico-chemical properties:

Color—dark brown; appearance—two separate layers; odor—sharp and stingy as of burned oil; d_4^{20} —1.004; n_D^{20} —1.485; viscosity in centistokes/20° C.—1200; distil. range/10 mm.—5%/145° C., 50%/238° C., 75%/292° C.; aniline point—plus 59° C.; acid No. 137; saponif. No. 256; carbonyl No. 138; unsaponif. matter—18%; naphthenic and hydroxy-naphthenic acids—39%; carbonyl-naphthenic acids—46%; volatile low molecular acids—5%; recovery—101 pounds.

This dark colored, malodorous, viscous liquid was oxidized in the same autoclave with a 45% aqueous solution of ammonium persulphate as follows:

For the recovered 101 pounds of the air oxidized product, about 250 pounds of the 45% aqueous ammonium persulphate solution was used. This amount was calculated in the same way as indicated in Example 1. First the 101 pounds of the air oxidized white oil was heated to a temperature of about 60° C. At this temperature, while stirring thoroughly, under atmospheric pressure, the calculated amount of 250 pounds of the 45% ammonium persulphate solution was slowly added and through the addition the temperature was maintained at about 55–60° C. by the use of a cooling bath. After the exothermic reaction was completed, the mixture was allowed to cool off to room temperature, at which temperature it was held while stirring thoroughly for about 26 hours. The oxidation reaction was considered as completed, when after one hour more, the saponification number of the oxidized product remained practically unchanged. Afterwards, the mixture was separated from the aqueous layer, which was discharged. The straw-yellow colored oily upper layer, was washed with small amounts of a warm saturated aqueous solution of sodium chloride and subsequently freed from the volatile, low molecular fatty acids by a short distillation with super-heated steam.

Further purification of the obtained dicarboxylic naphthenic acids, if necessary, is performed as described in Example 1 or 2.

Essentially, the two-step oxidation process under the present invention can be applied to any commercial white mineral oil, or any mineral oil, from which previously through exhaustive refining all aromatic and unsaturated compounds have been removed. Also it is important that the white mineral oil does not contain paraffin waxes. Paraffin waxes when oxidized with air, yield fatty- and hydroxy-fatty acids, which by further oxidation with aqueous peroxide solutions do not give the desired dicarboxylic naphthenic acids, as required under this invention, but give dark resinous and useless products. Therefore the success of this invention depends upon the proper selection of the white mineral oil, free from paraffin waxes and unsaturated and aromatic hydrocarbons. It is also proper to mention in this place, that by air oxidation alone from white mineral oils, dicarboxylic naphthenic acids cannot be obtained under any circumstances. I have found in my experiments that as soon as the maximum amount of the unsaponifiable matter is oxidized to monocarboxylic acids and their esters, as exemplified by Formulas II to VII, further air oxidation produces only resin-like dark useless products and not the desired light colored dicarboxylic naphthenic acids. Therefore the only way to arrive at such dicarboxylic naphthenic acids, is to interrupt the air oxidation process at the moment when no further conversion of unsaponifiable matter into carbonyl-naphthenic takes place and proceed with the oxidation using an aqueous solution of peroxide salts, which alone have the property to oxidize the carbonyl-, the methoxy-, and one of the methyl group into a second carboxyl group.

As is also evidenced in the specification and examples, the process of this invention is such that the desired dicarboxylic naphthenic acids can be produced economically, safely and efficiently, thus opening for the first time a new abundant source of this industrially important class of dicarboxylic acids.

It should be furthermore understood that the present invention is not based upon or dependent upon the theories which I have expressed, nor is the invention to be regarded as limited to the express procedure or material set forth, these details being given only by way of illustration and to aid in clarification of this invention.

Finally it shall be understood that I do not claim the process of air oxidation of white mineral oils into monocarboxylic acids as such.

What I claim is:

1. A two-step oxidation process for the manufacture

of predominantly dicarboxylic naphthenic acids from white mineral oils, which comprises, as the first step, oxidizing said oils with air at temperatures from 100° to 200° C., under pressure not higher than 10 atmospheres, in the presence of a catalyst belonging to the class of polyvalent heavy metal salts of fatty acids, whereby the oxidation is conducted until no appreciable increase in the carbonyl number of the oxidized oil occurs; said oxidation product being subjected to a second oxidation step, which comprises further oxidation with an aqueous solution of a peroxide salt, this final oxidation being conducted until no appreciable increase in the saponification number of the oxidized product occurs.

2. A two-step oxidation process for the manufacture of predominantly dicarboxylic naphthenic acids from white mineral oils, which comprises, as the first step, oxidizing said oils with air at temperatures from 100° to 200° C., under pressure not higher than 10 atmospheres, in the presence of a catalyst belonging to the class of polyvalent heavy metal salts of fatty acids, whereby the oxidation is conducted until no appreciable increase in the carbonyl number of the oxidized oil occurs; said oxidation product being subjected to a second oxidation step, which comprises further oxidation with an aqueous solution of a peroxide salt, at a temperature not higher than 100° C., said peroxide salt being present in a ratio of at least one mole for the carbonyl group in each mole of the carbonyl-naphthenic acids, at least two moles for the methoxy-group in each mole of the hydroxy-naphthenic acids, and at least three moles for one methyl group in the pentane ring of each mole of the naphthenic acids, said final oxidation being conducted until no appreciable increase in the saponification number of the oxidized product occurs.

3. A two-step oxidation process for the manufacture of predominantly dicarboxylic naphthenic acids from white mineral oils, which comprises, as the first step, oxidizing said oils with air at temperatures from 100° to

200° C., under pressure not higher than 10 atmospheres, in the presence of a catalyst belonging to the class of polyvalent heavy metal salts of fatty acids, whereby the oxidation is conducted until no appreciable increase in the carbonyl number of the oxidized oil occurs; said oxidation product being subjected to a second oxidation step, which comprises further oxidation with an aqueous solution of a peroxide salt, at temperatures not higher than 100° C., said peroxide salt being hydrogen peroxide, said hydrogen peroxide being present in a ratio of at least one mole for the carbonyl group in each mole of the carbonyl-naphthenic acids, at least two moles for the methoxy-group in each mole of the hydroxy-naphthenic acids, at least three moles for one methyl group in the cyclopentane ring of each mole of the naphthenic acids, said oxidation being conducted until no appreciable increase in the saponification number of the oxidized product occurs; said oxidized product being free from the low molecular volatile fatty acids by steam distillation and after washing and drying being further purified from unsaponifiable matter by selective extraction of the saponifiable matter with an aqueous solution of ethyl alcohol, and finally by fractionating vacuum distillation being divided into narrow fractions, each containing predominantly an individual dicarboxylic naphthenic acid.
